PICTURE FRAME

Carroll C. Miles, Leominster, Mass.

Application May 7, 1945, Serial No. 592,301

2 Claims. (Cl. 40—152)

1

This invention relates to picture frames or the like.

Objects of the invention include the provision of a picture frame comprising a novel slip in back construction for quick and easy insertion and removability of the glass and the picture without the use of any fasteners or the like; the provision of a novel and inexpensive picture frame having a sliding or slip in back, and guideways therefor, said guideways being originally formed integral with the sliding back and being separated and formed by cutting out during the process of manufacture of the picture frame; and the provision of a picture frame having superior appearance but made of inexpensive material such as cardboard, chipboard or the like, and comprising a frame forming the front or face frame having secured thereto at the rear surface thereof a stepped spacer board forming a glass well and a part of the guide for the slide or slip in back, the remainder of the guide being formed by the above described back unit comprising the back frame and the removable slip in back.

Further objects of the invention include the provision of a picture frame as above described and constructed for simple and easy removal and reinsertion of the slip in back, the latter being guided in such a way as to completely avoid any interference with the sliding action so that the slip in back is always easily inserted without catching or canting.

Other objects and advantages of the invention will appear hereinafter.

Reference is to be had to the accompanying drawings in which:

Fig. 1 is an elevational view showing the back of the completed frame;

Fig. 2 is a view similar to Fig. 1 but showing the slip in back partially removed;

Fig. 3 is an edge view of the frame of Fig. 1 looking in the direction of arrow 3;

Fig. 4 is a section of line 4—4 of Fig. 1;

Fig. 5 is a longitudinal section of the complete frame with the slip in back removed;

Fig. 6 is a view showing the blank from which the back of the frame is made;

Fig. 7 is a view showing the blank from which the stepped spacer board is made, and

Fig. 8 is an edge view of the blank of Fig. 7 looking in the direction of arrow 7.

Referring first to Fig. 1 and Fig. 2, the present invention comprises in general, a frame 10 and a removable back 12, the latter being slidably removable and insertable in the frame 10. The

2

back 12 may be referred to as a "slip in" back and is provided with an easel 14 which may have a pair of right angle edges as at 16 for supporting the frame either upright or on a side edge 5 thereof.

The frame 10 is made up of a generally rectangular open frame board 18 forming the face of the frame, and this board may be appropriately decorated as by embossing or ornamental coverings which do not form any part of the present invention. However, the frame board 18 forms a support for the glass around the edges thereof as illustrated in Fig. 4. Superimposed on the frame board 18 there is a spacer board which 10 is made as illustrated in Fig. 7 and Fig. 8. A piece of board of desired size is cut out in the center as at 22 to form an opening and two corners are cut off as of 24 for a purpose to be described.

20 This blank is scored along the lines 26 forming side elements 28 and a top element 30 which are folded over to rest in superimposed position on the blank as indicated in broken lines 32. The elements 28 and 30 are narrower than the remainder of the frame so that the spacer board 15 is finally formed having steps clearly shown in Figures 4, 5, and 8, the bottom steps being formed of the parts 34 and the second smaller steps by the elements 28 and 30. It is to be noted that the 25 spacer board is open at the bottom as at 36 in Fig. 5, except for the original layer 34, and it will be seen that the glass 20 rests on frame 18 completely around the periphery thereof and is contained laterally by the elements 34 of the 30 frame which extend all the way around the edges of the glass. Naturally, the picture will rest directly on the glass.

The back of the frame is formed from a single blank illustrated in Fig. 6 and having a portion 40 38 wider and longer than the integral portion 40. The portion 40 is folded over on portion 38 forming the broken line location 42 and the two parts are glued together. This double back 45 is then superimposed on the rear of the front frame above described with portion 40 fitting in the opening defined by the spacer board elements 28 and 30, with portion 38 now lying at the top. The portion 38 is glued about its edges to the spacer board elements 28 and 30 so that the 50 portion 40, altho glued to portion 38, is free of the spacer board frame. The edges of portion 38 which are glued to the spacer boards are indicated as 58 in Figs. 1, 2, and 6.

With the parts in this position, the blank portion 38 is cut as by a die along a line starting

at point 44 in Fig. 1, continuing around on a line 46 to a point 48 and also along lines 50 forming the easel. The lines 52 represent scores so that the easel, altho attached to the back, may pivot on score lines 52. The frame is now complete except for cutting along line 54 to free the end of the easel from the back. It is particularly pointed out that the cutting operation just above described, applies only to the portion 38 and since this portion has been glued around its edges to the step 28 and 30, a back is formed in the shape shown best in Fig. 2 and therefore the slip in back 12 is produced. The edges as at 56 of the portion 40 form tongues which are located to slide on the frame board step 34 in lateral contact with elements 28 and under elements 58 formed from portion 38 of the original blank shown in Fig. 6. Also, the portion 40 extends up under a part 60 of the original blank portion 38 and the remainder of the latter forms the back from which the easel is cut.

Hence, the slip in back is neatly held down by the elements 58 and 60 which originally were a part of the back as has been described.

From the above description, it will be seen that the slip in back 12 has a pair of side tongues 56 and a top or inner portion 62 which are slidably guided on elements 34 and under elements 58 and 60 having lateral engagement with the elements 28. The slip in back is cut out along the curved line 64 to form an accurate locating means therefor so that the slip in back always comes to rest in the same relation to the front frame. Also, the original portion 38 is cut on curves 66, Fig. 2, to separate the slip in back so it may be released and withdrawn and also to locate the slip in back at this end and to provide an easy entering guide.

The slip in back may be covered with ornamental material prior to its assembly in which case cutting along lines 46 and 54 completes the frame ready for shipment, or ornamental material may be applied to the front frame 18 and folded over the edges of the back frame 10 after assembly of the parts. When the frame is completed, the part 10 is U-shaped, having its closed end uppermost and the legs depending, the legs being spaced and open at the bottom, receiving the slip in back 12.

Having thus described my invention and the advantages thereof, I do not wish to be limited to the details herein disclosed, otherwise than as set forth in the claims, but what I claim is:

1. A picture frame comprising an open con-

tinuous front face frame, an open stepped spacer frame thereon, the spacer frame being substantially aligned at its exterior edges with the corresponding edges of the front face frame, but having its inner edges terminating short of the inner edges of the front face frame to form a plurality of steps, one step forming a well for a pane of glass or the like, a back including two parts, one of which is U-shaped and secured in fixed overhanging relation to the spacer frame to form a guideway and the other part being slidably guided therein and having a stepped periphery to interfit in said guideway and to form a continuous flat surface with the U-shaped part at the back of the picture frame, the edge of the said other part bearing on another said step to prevent lateral motion.

2. Method of making a picture frame comprising the steps of assembling an open front face frame and an intermediate open spacer frame, forming a blank having a portion smaller than the remainder thereof, folding the smaller portion over on the larger remainder of the blank, securing the folded blank portions together, placing the folded blank on the spacer frame with the smaller portion underneath and fitting in the spacer frame, securing the overhanging edges of the larger portion of the blank to the spacer frame, and cutting out a central portion of the larger portion of the blank inwardly of the edges of the smaller portion thereof, to leave the smaller portion edges free of and under the edge portions of the larger blank portion which are secured to the spacer frame.
